12 Claims. (Cl. 86—27)

The present invention relates to hydraulic drive automatic machines, that is to say machines intended to perform on pieces to be treated operations of any kind, for instance machining, finishing, filling, packing operations, at least some of the parts which cooperate in performing these operations being operated through a hydraulic transmission. The invention is more especially, although not exclusively, concerned, among these machines, with those utilized for charging shells, and especially small shells.

The chief object of the present invention is to provide a machine of this kind which is better adapted than those used up to this time to meet the requirements of practice.

The essential feature of the present invention consists in arranging such a machine in such manner that, at least for some of the operations thereof, the end of a phase of operation produces the starting of the next phase, whereby the latter can take place only when the preceding phase is finished.

Other features of the present invention will result from the following detailed description of some specific embodiments thereof.

Preferred embodiments of the present invention will be hereinafter described, with reference to the accompanying drawings, given merely by way of example, and in which:

Fig. 1 is a longitudinal sectional view of a machine for charging shells made according to the present invention;

Fig. 2 shows, on an enlarged scale and in axial section, a detail of this machine;

Fig. 3 is a plane view of the same machine, with parts in section;

Fig. 4 is a part elevational view of the same machine, on the line IV—IV of Fig. 3;

Fig. 5 is a part elevational view of the same machine, on the line V—V of Fig. 3;

Fig. 6 is a plan view of the same machine according to the invention;

Fig. 7 is a sectional view on the line VII—VII of Fig. 6;

Fig. 8 is a part side view corresponding to Figs. 6 and 7;

Fig. 9 is a plan view showing some elements of the machine.

In the following description with reference to the drawings above described, I will set forth the structure and operation of a hydraulic drive automatic machine serving, for instance, to the charging of small size shells 1.

According to the chief feature of the present invention, this machine is arranged in such man-

ner that, for at least some of the phases of operation thereof, the end of a phase produces the starting of the next phase, whereby said second mentioned phase can take place only when the preceding one is finished.

It will be readily understood that such an operation will greatly improve the safety of working of the machine since all the pieces delivered by said machine have necessarily undergone integrally each of the operations which ensure, at the end of their execution, the starting of the next phase of operation.

If, for some accidental reason, one of these phases cannot be wholly performed, the next phase cannot be started and the machine ceases working, without undergoing any injury and without deteriorating the shells which are being charged. It will then suffice to remedy the cause that has prevented the phase in question from being wholly performed, and the machine will then finish this phase and go on with its work.

Preferably, as it will be supposed in the following description, the machine is of the drum or barrel type, that is to say it includes a horizontal plate or disc 2, moving with a discontinuous rotary motion, on which the shells to be charged are disposed, said disc feeding said shells successively on the vertical line of distributing devices which permit of introducing a charge of powder thereinto, and of compressing devices capable of placing said charge under the desired pressure.

It is, for instance, possible, to arrange the system in such manner that the charging of each shell is effected in two steps, the first charge that is introduced being compressed before the introduction of the second charge.

Advantageously, such a machine may be made in such manner as to work as follows: unlocking of plate 2, driving of the latter through a certain angle, locking of said plate in its new position, and operation of the distributing and compressing devices.

If the chief feature of the present invention is applied, as it seems advantageous to do, to all the phases of this cycle of operation, the hydraulic control system of the machine is to be arranged in such manner as to comply with the following conditions:

Plate 2 cannot be imparted a rotary movement after it has been locked;

The locking system of said plate cannot again come into action as long as plate 2 has not reached its new position;

The distributing and compressing devices can-

not come to coat with the shells opposite which they are located as long as plate 2 is not again locked in position;

Finally, said plate cannot be unlocked, or released as long as said distributing and compressing devices have not come back into inactive position.

Although, in view of these principles, it is possible to devise many specific embodiments of such a machine, I have found that it is of advantage to have recourse to the embodiment illustrated by the accompanying drawings.

According to this embodiment, the machine is provided with a hollow base in which can be housed an oil tank, and, eventually, the pump for placing the plant under pressure. The return of oil resulting from the discharge of the various control circuits of the machine takes place inside said hollow base at the upper part of which plate 2 is mounted, as it will be herein-after more specifically explained.

Coaxially with this base, I provide a rod 4 capable of sliding, against the action of an elastic system such for instance as a spring 5, on the inside of a cylinder disposed partly on the inside of said base, said rod acting as support for the compressor devices and further ensuring, upon certain vertical displacements thereof, the operation of the distributing devices.

Plate 2 is then mounted in such manner that it pivots about the upper part of cylinder 6, said plate being provided with lugs 7, preferably uniformly distributed over its periphery, so that the shells 1 can be fitted on said lugs.

Plate 2 is provided with a drive system working only in one direction. This system may consist, for instance, of a free wheel pinion 8 subjected to the action of a rack 9.

I further provide a locking device for stopping, at the desired time, plate 2, and for this purpose, for instance, I fit in the upper part of base 3, a finger 10 capable of projecting, under the action of a spring 11, into any of a plurality of holes 12 provided at suitable angular intervals, in the lower face of said plate.

I have recourse, for operating the various elements above mentioned, to a hydraulic system which is advantageously devised (account being taken of the fact that the phases of operation of the machine depend upon one another) in such manner as to include three distinct circuits A, B and C, corresponding respectively to the operation of finger 10, the drive of plate 2, and the control of the vertical displacements of the rod 4.

Concerning the first of these circuits, it is made as follows:

I provide, in the upper part of base 3, an oil feed conduit A1 which is caused to communicate, through an annular groove A2 carried by rod 4 and playing the part of distributing means when said rod undergoes vertical displacements, as will be hereinafter explained, with a conduit A3 which is prolonged by a conduit A4 extending in the rack 9 (when the latter is in position of rest) through a passage A5 and opening (said conduit A4) into a cylinder 13 above a piston 14, rigid with finger 10, whereby an increase in the liquid pressure inside said cylinder produces the retraction of said finger against the action of its return spring 11.

One of the elements moving simultaneously with plate 2, for instance rack 9, is adapted to control a system capable of ensuring the discharge of cylinder 13. For instance, this system is constituted by providing, in the body of rack 9,

a passage capable of connecting conduit A4 and cylinder 13 with the inside of base 2, that is to say with the discharge tank, when this rack has moved through a part of its stroke.

Concerning now circuit B, it is arranged in such manner that it is placed under pressure as a result of the depressing of finger 10 and, on the contrary, that its discharge can take place when said finger projects into holes 12.

For this purpose, for instance, the oil feed conduit B leads to an orifice B1 opening into the inside of cylinder 13, in which is movably fitted piston 14, rigid with finger 10. An orifice B2 is provided, opposite orifice B1, which is prolonged by a conduit B3 leading to a cylinder 16 in which a piston 18 rigid with rack 9 is movable, against the action of a return spring 17.

The skirt of piston 14 is arranged in such manner that, on the one hand, when finger 10 is in locking position, orifice B1 is hidden and orifice B2 is opened, owing to a port 19 which permits the discharge of the circuit that is considered through the bottom of cylinder 13, and, on the other hand, when said finger is retracted, an annular groove carried by piston 14 connects orifices B1 and B2, thus permitting of placing cylinder 16 under pressure.

Finally, concerning circuit C, which is to control the displacements of rod 4 and the distributing and compressing devices combined with said rod, it is advantageously devised in such manner that its placing under pressure is produced by rack 9, at the end of the useful stroke thereof.

For this purpose, for instance, the liquid under pressure is fed through a conduit C into a chamber 21 containing an evacuation orifice which is normally closed by a valve 22 kept on its seat by means of a spring 23.

In order to obtain the opening of this valve at the desired time, I make use of a kind of piston 24 adapted to be displaced by rack 9 at the end of the driving stroke thereof in such manner as to come, in this case, to move said valve away from its seat, and, at the same time, to close a discharge orifice 25, thus placing chamber 21 in communication with a conduit C1 which itself opens into cylinder 6, above a piston 26, rigid with rod 4.

I provide means for keeping piston 24 in the position for which valve 22 is opened, for the time corresponding to the distribution and compression operation.

These latter means are constituted, for example, by a sliding piece of which the lower part 27 forms a little piston which carries the upper part 27¹, the latter part having a diameter less than that of the piston 27.

The left-hand part of the piston 24 is formed as a fork 24¹ (see Fig. 3) which engages with its legs the upper part 27¹ of the sliding piece. The sliding piece includes an extension 29 engageable by a finger 30 rigid with the rod 4 at the end of its descending course.

The sliding piece 27, 27¹ is also submitted to the action of a spring 28 which presses the part 27 against a shoulder or enlargement 24² of the piston 24 when the latter is in the normal position in Figs. 3 and 4.

When, on the other hand, the piston 24 is moved to the right to produce the opening of valve 22, the enlargement 24² disengages the slide piece 27, 27¹, which then moves upwardly. The lower part 27¹ of the slide piece, under the action of spring 28, then engages with its lateral face 27³ against the left-hand face 24³ of en-

largement 24². Thus the piston 24 is locked in its right-hand position, and holds the valve 22 open against the spring 23.

When, on the other hand, the rod 4 has completed its downward movement, finger 30 engages rod 29 and pushes the slide piece 27, 27¹ downward, thus disengaging the portion 27² from the left hand face 24³. Piston 24 is then pushed towards the left by the spring 23, and engagement 24² comes back into a position to overlie the slide piece portion 27 and hold it in its lowered position.

For the sake of clarity, I will indicate now, before entering into details concerning the structures of the distributing and compressing devices proper, how circuits A, B and C above referred to work and control one another.

Considering the machine at a time of its operation when finger 10 is engaged in a hole 12 and rod 4 is in the upper position, that is to say after a charging operation, annular groove A2 occupies a position in which it connects conduits A1 and A3 with each other, thus permitting the oil pressure to be transmitted, through conduit A4, as far as cylinder 13. Therefore, piston 14 is moved against the action of spring 11 and this displacement has for its effect, on the one hand, to produce the retraction of finger 10, which then releases plate 2, and, on the other hand, to bring groove 20 opposite orifices B1 and B2, that is to say to close circuit B.

Once this last circuit is closed, the oil pressure is transmitted into cylinder 16, and rack 9 is moved, against the action of spring 18, in the direction in which it drives disc 2 through a suitable angle. When said rack has moved a portion of its stroke, recess 15 comes opposite conduit A4 and circuit A is discharged. Finger 10 is urged toward its upper position but it cannot move under the effect of spring 11 as long as it is not opposite a hole 12, that is to say as long as disc 2 has not reached the new position in which it is to be stopped. When this position is reached, the locking of disc 2 and the discharge of circuit B take place simultaneously, since the upward movement of groove 20 places orifice B2 into communication with the discharge circuit of the whole of the machine, while closing orifice B1. But immediately before these two operations take place, rack 9 produces, at the end of its stroke, the displacement of piston 24 which is hooked on small disc 27 in the position in which it closes the discharge orifice 25 and keeps valve 22 opened against the action of spring 23, that is to say in a position in which it ensures the placing under pressure of circuit C. Circuit B is no longer under pressure due to the fact that groove 20 has moved upwardly, and rack 9 comes back into its initial position under the effect of spring 17.

Once circuit C is thus closed, the oil pressure comes to act on piston 26, which moves down under the effect of said pressure against the action of spring 5, thus driving, together with it rod 4 and the devices associated therewith, which will be hereinafter more fully described. As soon as the downward movement of this rod has started, groove A2 is displaced with respect to conduits A1 and A3, which positively prevents any accidental unlocking of plate 2, as long as rod 4 has not come back into its initial position. When said rod reaches its lower position, finger 30 comes to coact with lug 29, which is rigid with small disc 27, compelling the latter to release piston 24, which comes to occupy a posi-

tion in which circuit C is discharged. Rod 4 comes back into high position, and as groove A2 again connects conduits A1 and A3, the unlocking of finger 10 can take place and the same cycle of operations again takes place.

It is then possible to perform manually the filling of the shell supports as soon as these loaded shells have been removed, also manually. This replacement of the charged shells by new shells to be charged takes place when plate 2 brings said charged shells in a clear zone, after which the fresh shells thus mounted are passed to the distributing and compressing devices.

Concerning now the two compressing devices to be provided, they can be made for instance in the following manner:

I provide, at the upper part of rod 4, a fork 31, each arm of which supports a punch 32 capable of engaging into the shell 1 for compressing the charge poured into said shell by one of the distributing devices.

I leave, between the branches of said fork, an interval sufficient for the housing of the distributing device intended to introduce the second charge.

Advantageously, I interpose, between fork 31 and each punch 32, a spring box or the like 33, preferably of adjustable tension, capable of limiting to a suitable value the rate of charging compression, said value being not affected by slight variations of the stroke of rod 4.

Furthermore, advantageously, one of the arms of fork 31 carries the finger 30 intended to ensure the release of disc 27.

Concerning now the distributing devices, I provide, for instance, two such devices, as above explained, and I arrange them in such manner that they are controlled by rod 4, during its downward stroke, and then ensure the release of a charge, for instance of powder, previously measured in such manner that all the shells receive the same charge.

Of course, distributing devices complying with these conditions can be made in many different manners, but I consider that it is advantageous to make use of the following arrangement, illustrated by the accompanying drawings:

Each of the distributors is provided with a fixed hopper 34 communicating, through the intermediate of an obturator 35, which permits of separating said hopper, for instance when the remainder of the system is taken to pieces, with a distributing and measuring slide valve 36 capable of occupying either of the two following positions:

(a) A position in which a hole 37 provided in said slide valve is located under obturator 35 and is thus filled with a charge of powder; and

(b) A position in which said cavity 37 comes above the shell to be charged and drops its charge, through an orifice 38, into said shell, which can, with advantage, be fitted with a funnel 39.

In order to control the sliding displacements of slide valve 36, I provide a bent lever 40 one of the arms of which is provided with a ball 41 engaging in a notch 42 provided for this purpose in said slide valve. The other arm of said lever coacts, through the intermediate of a rod 43 and a spring 43' intended to permit, eventually, a complementary displacement of lever 40 after slide valve 36 has reached the end of its stroke, with a bent piece 44 mounted on the end of fork 31 which is rigid with rod 4, the whole being such that, when rod 4 moves in the opposite direc-

tion, said slide valve comes back under hopper 34 so as to receive a new charge.

It should be noted that it is possible, advantageously, to constitute slide valve 36 of a fibrous material, such for instance as that known by the trade name Celeron which does not risk producing sparks as a result of its friction with the metallic slideway in which said slide valve is movable.

The latter is made of two parts which are 10 kept applied against said slideway by springs 45, in order to reduce the risks of jamming, crushing and spontaneous ignition of the powder flakes.

Anyway, whatever be the embodiment that is chosen, I obtain a machine adapted to work automatically for charging shells the operation and advantages result sufficiently clearly from the above explanations for making it unnecessary further to describe said operation and to stress said advantages.

In a general manner, while I have, in the above description, disclosed what I deem to be a practical and efficient embodiment of the present invention, it should be well understood that I do not wish to be limited thereto as there might be changes made in the arrangement, disposition and form of the parts without departing from the principle of the present invention as comprehended within the scope of the appended claims.

What I claim is:

1. In a device for charging cartridge cases, which comprises a rotatable table for receiving cases to be charged, a first means to impart intermittent rotary movement to said table, a second means to lock said table against movement, and a third means operating in a cycle to charge cases carried by said table; first, second and third hydraulic circuits for operating in one direction, and first, second and third spring means for operating in the opposite direction each of said first, second and third means, respectively, control means for said circuits, including means to control said second circuit in response to the operation of said first and third means, respectively, to render said second circuit inoperative when either of said first and third means is operated, means to control said first circuit in response to the operation of said second means to render said first circuit inoperative when said second means is operated to lock said table, means to control said third circuit in response to the operation of said first means, and means responsive to operation of said third means to render said third circuit inoperative when said third means has completed a predetermined portion of a cycle of operations.

2. In a device for charging cartridge cases, which comprises a rotatable table for receiving cases to be charged, a first means to impart intermittent rotary movement to said table, a second means to lock said table against movement, and a third means operating in a cycle to charge cases carried by said table; first, second and third hydraulic circuits for controlling movement in one direction of each of said first, second and third means, respectively, spring means for controlling movement in the opposite direction of each of said first, second, and third means, control means for said circuits, including a first and a second control element in the second circuit, means to control said first and second control elements in response to the operation of said first and third means, respectively, to render said sec-

ond circuit inoperative when either of said first and third means is operated, a third control element in said first circuit, means to control said third element in response to the operation of said 5 second means to render said first circuit inoperative when said second means is operated to lock said table, a fourth control element in said third circuit, means to control said fourth control element in response to the operation of said first means to render said circuit operative, and means responsive to operation of said third means to control said fourth element to render said third circuit inoperative when said third means has completed a predetermined portion of a cycle of operations.

3. In a device for charging cartridge cases, which comprises a rotatable table for receiving cases to be charged, means to impart intermittent rotary movement to said table, a second 15 means to lock said table against movement, and a third means operating in a cycle to charge cases carried by said table; first, second and third hydraulic circuits operative in one direction and spring means for operating in the other direction each of said first, second and third means, respectively, said first means including a first member which reciprocates in a cycle, said third means including a second member which reciprocates in a cycle, means controlled by the beginning of movement of said first member in its 20 cycle to render said second circuit inoperative, means controlled by movement of said second member to render said second circuit inoperative, said second means including a third reciprocating member, means operated by movement of said third reciprocating member to render said first circuit operative, and means controlled by movement of said first reciprocating member to render said third circuit operative, means to lock said last controlled means in position to maintain said third circuit operative, and means controlled by movement of said second reciprocating member to release said locking means and to restore said third circuit to inoperative 25 condition.

4. In a device for charging cartridge cases, which comprises a rotatable table for receiving cases to be charged, means to impart intermittent rotary movement to said table, a second 30 means to lock said table against movement, and a third means operating in a cycle to charge cases carried by said table; first, second and third hydraulic circuits for operating in one direction and spring means for operating in the opposite direction each of said first, second and third means, respectively, said first circuit when charged causing operation of said first means to move said table, said second circuit when charged causing release of said second locking means, 35 and said third circuit when charged causing movement of said third means through at least a part of its cycle, said first means including a first member which reciprocates in a cycle, said third means including a second member which reciprocates in a cycle, means controlled by the beginning of movement of said first member in its cycle to render said second circuit inoperative, means controlled by movement of said second member to render said second circuit inoperative, said second means including a third reciprocating member, means operated by movement of said third reciprocating member to unlock said table to render said first circuit operative so as to move said table, and means controlled by 40 movement of said first reciprocating member to

render said third circuit operative to charge cases, means to lock said last controlled means in position to maintain said third circuit operative, and means controlled by movement of said second reciprocating member to release said locking means and to restore said third circuit to inoperative condition.

5. In a device for charging cartridge cases, which comprises a rotatable table for receiving cases to be charged, a reciprocating rack, a gear meshing with said rack, a one-way clutch connection between said gear and said table, a member mounted for reciprocation, means carried by said member for charging cartridge cases carried by said table, said table having holes therein, and a reciprocable pin engageable in said holes for locking said table in predetermined angular positions; first, second and third hydraulic circuits for moving said rack, for moving said pin and for moving said reciprocating member respectively, a cylinder, a piston slideable in said cylinder rigid with said rack, means connecting said cylinder to said first circuit to drive said rack in a direction to turn said table when said first circuit is charged, spring means urging said rack in the other direction, said piston including means for rendering said second circuit operative when the piston is at rest and for rendering said second circuit inoperative after said piston has begun its movement, a second piston rigid with said pin and subjected to the action of fluid in said second circuit, said piston when subjected to such pressure moving said pin to unlocking position out of engagement with said holes, spring means acting on said piston to urge said pin into engagement with said holes, said piston having means arranged in said first circuit for rendering said first circuit inoperative when said pin is in locking position within one of said holes, a valve in said third circuit, spring means normally holding said valve to closed position, means engageable by said first piston at the end of its stroke in the direction to move said table to engage said last valve and move it to open position so as to render said third circuit operative, catch means for engaging said member when it is moved to a position to render said third valve operative to lock said member and valve in operative position, means engageable by said reciprocating member upon its movement in a direction to charge said cases and at the end of such movement to release said locking means whereby said third valve is restored to circuit closing position, said reciprocating member including means operable at the beginning of its movement to close said second circuit so as to render said second circuit inoperative, and to open said second circuit upon its return to normal position.

6. In a device for charging cartridge cases, which comprises a rotatable table for receiving cases to be charged, a reciprocating rack, a gear meshing with said rack, a one-way clutch connection between said gear and said table, a member mounted for reciprocation, means carried by said member for charging cartridge cases carried by said table, said table having holes therein, and a reciprocable pin engageable in said holes for locking said table in predetermined angular positions; first, second and third hydraulic circuits for moving said rack in a direction to move said table, for moving said pin out of locking position and for moving said reciprocating member towards charging position respectively, a cylinder, a piston slideable in said cylinder rigid with

said rack, means connecting said cylinder to said first circuit to drive said rack in a direction to turn said table when said first circuit is charged, spring means urging said rack in the other direction, said piston including means for rendering said second circuit operative when the piston is at rest and for rendering said second circuit inoperative after said piston has begun its movement, a second piston rigid with said pin and subjected to the action of fluid in said second circuit, said piston when subjected to such pressure moving said pin to unlocking position out of engagement with said holes, spring means acting on said piston to urge said pin into engagement with said holes, said piston having means arranged in said first circuit for rendering said first circuit inoperative when said pin is in locking position within one of said holes and for rendering said first circuit operative when said pin is in unlocking position, a valve in said third circuit, spring means normally holding said valve to closed position, means engageable by said first piston at the end of its stroke in the direction to move said table to engage said last valve and move it to open position so as to render said third circuit operative, catch means for engaging said member when it is moved to a position to render said third valve operative to lock said member and valve in operative position, means engageable by said reciprocating member upon its movement in a direction to charge said cases and at the end of such movement to release said locking means whereby said third valve is restored to circuit closing position, said reciprocating member including means operable at the beginning of its movement to close said second circuit so as to render said second circuit inoperative, and to open said second circuit upon its return to normal position.

7. In a device for charging cartridge cases, which comprises a rotatable table for receiving cases to be charged, a reciprocating member, a one-way connection between said member and said table, a second member mounted for reciprocation, means carried by said second member for charging cartridge cases carried by said table, said table having holes therein, and a reciprocable pin engageable in said holes for locking said table in predetermined angular positions; first, second and third hydraulic circuits for moving said first member in a direction to move said table, for moving said pin out of locking position and for moving said second reciprocating member towards charging position respectively, means operated by said first member for rendering said second circuit operative when said first member is at rest and for rendering said second circuit inoperative after said first member has begun its movement, a piston rigid with said pin and subjected to the action of fluid in said second circuit, said piston when subjected to such pressure moving said pin to unlocking position out of engagement with said holes, spring means acting on said piston to urge said pin into engagement with said holes, means arranged in said first circuit controlled by said piston for rendering said first circuit inoperative when said pin is in locking position within one of said holes and operative when said pin is out of locking position, means controlled by said first member at the end of its stroke in the direction to move said table to render said third circuit operative, catch means for engaging said last means when it is moved to a position to render said third circuit operative to lock said

last means in operative position, means engageable by said second reciprocating member upon its movement in a direction to charge said cases and at the end of such movement to release said locking means whereby said third circuit is rendered inoperative, said second reciprocating member including means operable at the beginning of its movement to close said second circuit so as to render said second circuit inoperative, and to open said second circuit upon its return to normal position.

8. In a device for charging cartridge cases, which comprises a rotatable table for receiving cases to be charged, a first means to impart intermittent rotary movement to said table, a second means to lock said table against movement, and a third means operating in a cycle to charge cases carried by said table; first, second and third hydraulic circuits for operating each of said first, second and third means, respectively, control means for said circuits, including a first control element in the circuit for operating said second means, means to control said first control element in response to the operation of said first means to render said second circuit inoperative when said first means is operated, a second control element in said first circuit, means to control said second element in response to the operation of said second means to render said first circuit inoperative when said second means is operated, a third control element in said third circuit, means to control said third control element in response to the operation of said first means, and means responsive to operation of said third means to control said third element to render said third circuit inoperative when said third means has completed a predetermined portion of a cycle of operations.

9. An automatic machine for filling ammunition shells, comprising a horizontal table for holding shells to be filled, means to impart a discontinuous rotary movement to said table, two operating assemblies associated with said table, each of which comprises a distributing device for a charge of powder and a compressing device for compressing this charge in a shell, said device bringing each shell successively beneath both said devices so that they effect charging in two successive phases, each distributing device comprising a stationary hopper, a metering and distributing slide valve having a bore therein, and means connecting said hopper and said slide valve, an obturator in said connecting means to shut off said hopper from said valve, said valve being movable between a position in which said bore is located below the connecting means and thereby becomes filled with a charge

of powder and a position above the shell to be filled to release its charge into said shell, said slide valve comprising two relatively movable parts, and spring means urging said parts away from each other.

10. An automatic machine for filling ammunition shells, comprising a horizontal table for holding shells to be filled, means to impart a discontinuous rotary movement to said table, a stationary hopper, a metering and distributing slide valve having a bore therein, and means connecting said hopper and said slide valve, said valve being movable between a position in which said bore is located below the connecting means and thereby becomes filled with a charge of powder and a position above the shell to be filled to release its charge into said shell, said slide valve comprising two relatively movable parts, and spring means urging said parts away from each other.

11. A machine of the type described comprising in combination a stationary base, a table rotatable with respect to said base, driving means for imparting intermittent rotary movement to said table, indexing means comprising locking and abutment means supported respectively by said base and said table, a first fluid circuit for imparting movement to said driving means in one direction from its position of rest, means for returning said driving means to its position of rest, constantly acting means for urging said locking means into engagement with said abutment means, and a second fluid circuit for disengaging said locking means from said abutment means, means to control said first circuit in response to the operation of said locking means so as to render said first circuit operative when said locking means are disengaged and inoperative when said locking means are engaged, and means to control said second circuit in response of said driving means so as to render inoperative said second circuit when said driving means is out of its position of rest.

12. A machine according to claim 11 further comprising tool means operating in a cycle, a third fluid circuit for operating said tool means, means responsive to the operation of said driving means to render said circuit operative, means responsive to the operation of said tool means to render said circuit inoperative when said tool means has completed a predetermined portion of a cycle of operations and further control means for said second circuit responsive to the operation of said tool means so as to render inoperative said second circuit when said tool means is out of its position of rest.
